(57) **CLAIM**

The ornamental design for a headwear article as shown and described.

DESCRIPTION

FIG. 1 is a front-left perspective view of a headwear article according to the claimed design.

FIG. 2 is a front view of the headwear article.

FIG. 3 is a rear view of the headwear article.

FIG. 4 is a right side view of the headwear article.

FIG. 5 is a left side view of the headwear article.

FIG. 6 is a top view of the headwear article; and,

FIG. 7 is a bottom view of the headwear article.

The dash-dot broken lines in the drawings represent stitching that forms no part of the claimed design.

The short parallel lines extending across the narrowed side sections of the headwear article in FIGS. 1-2 and 4-6 of the drawings represent stitching that forms part of the claimed design.

The surface line shading is included for clarification purposes.
